(57) **CLAIM**

The ornamental design for a blow-off valve body, as shown and described.

DESCRIPTION

FIG. 1 is a top-front-left perspective view of a blow-off valve body showing my new design;

FIG. 2 is a bottom-rear-right perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken line showing vent apertures and an internal cavity in FIGS. 1 through 4; the mounting lug in FIGS. 1, 2, 3, 4, 5, 6, and 8; the lateral notches in FIGS. 1 through 6; and the fastener perforations in FIGS. 1, 2, 5, 6, 7, and 8 is included for the purpose of illustrating environmental structure and forms no part of the claimed design.
